UNITED STATES PATENT OFFICE.

JAMES E. YORK, OF NEW YORK, N. Y., ASSIGNOR TO YORK ROLLING PROCESS COMPANY,
A CORPORATION OF NEW YORK.

PROCESS FOR REROLLING METAL SHAPES FROM OLD RAILROAD-RAILS.

938,197.

Specification of Letters Patent. Patented Oct. 26, 1909.
Application filed September 10, 1903. Serial No. 172,648.

To all whom it may concern:

Be it known that I, JAMES E. YORK, a citizen of the United States, and a resident of the borough of Brooklyn, county of Kings, city and State of New York, have invented certain new and useful Improvements in Processes for Rerolling Metal Shapes from Old Railroad-Rails, of which the following is a specification.

- 10 This invention provides certain new processes for rerolling old rails into I-beams, heads and chairs of compound rails and various other shapes having one or more two-flanged heads. This rerolling improves the 15 quality of the metal. Furthermore the product is valuable because made from steel which has already stood the test of hard use. Such a manufacture involves substantially no change of any portion of the rail except 20 the head, the base flange and the web being unchanged in form in use as a rail and being therefore available without modification or reshaping unless it be to reduce the dimensions. An important feature of the process 25 is the forming of a groove in the top of the rail head by pressure in line with the web, which groove separates the head into two flanges. These flanges may then be bent 30 and reduced if necessary to the desired positions and dimensions to form a Y-shaped chair or the I-beam illustrated, or any other shape having a two-flanged head. Preferably the rail head is first reshaped on 35 its under side faces to bring these more nearly parallel with the web, so that the flanges formed by grooving the top of the head shall be of nearly uniform thickness throughout their width. Preferably also 40 the groove in the top of the rail head is formed while the web is held between opposite rolls, the groove being formed by means of a third roll with its axis perpendicular to the main rolls, the pressure of the grooving roll being exerted in the same direction as 45 that which the shape will receive in actual use, and having the effect of compacting and refining the grain of the wearing surface and thereby making it dense, hard and durable. The rerolled shape is given the maximum

durability by accomplishing the rerolling at 50 a low red heat instead of at the high temperature at which rails are commonly rolled.

I will proceed to describe the invention more in detail with reference to the accompanying drawings illustrating embodiments 55 of the invention.

Figure 1 is a side elevation of a set of rolls used in making an I-beam. Figs. 2 to 7 inclusive are enlarged portions of Fig. 1 illustrating more clearly the successive stages of 60 the process. Fig. 8 illustrates a modification of the process of Figs. 1 to 7.

Referring to the drawings, the apparatus comprises a pair of horizontal rolls T and U and a pair of vertical side rolls V and W. 65 The successive passes are numbered consecutively from 1 to 6 and are illustrated successively in Figs. 2 to 7 on a larger scale showing more clearly the modifications which take place in the contour of the rail. 70

An important improvement is the grooving of the top of the rail head so as to spread it into two flanges, which flanges are subsequently bent and reshaped as may be necessary to obtain the final product desired. The grooving is accomplished in 75 pass No. 3. Since the two flanges are to be ultimately at right angles to the web the groove which is formed is wide and shallow. As the base flange of the rail is considerably 80 wider than the flange which can be formed from the rail head, I prefer (where the common type of I-beam with approximately equal flanges is desired) to reduce the width 85 of the base flange of the rail in this and also in the other passes in which the rail travels on its side between the rolls. Also I-beams

are usually formed with webs of less thickness than the webs of rails of the same height. Consequently I prefer to reduce the 90 thickness of the web in pass No. 3 and also in the other passes in which the rail travels on its side. The dotted lines indicate clearly without any further description the shape 95 of the rail as it goes into pass No. 3 and the changes which occur in this pass. Preferably in this case as in Fig. 1 the under faces of the rail head are reshaped to form a

taper S more nearly coinciding with the direction of the web so that the flanges R R' to be subsequently formed shall have a regular shape of substantially the same thickness throughout or at least of not less thickness at their inner or lower portions than at their outer edges. This is accomplished in pass No. 2 (Fig. 3). The dotted lines show the change of contour and show also the reduction in the thickness of the web and the width of the base flange which is accomplished in this pass.

Fig. 2 illustrates a step which may be employed whereby the flanges R R' are made of the same length. According to Fig. 2 the rail in pass No. 1 is flattened on the top so as to be substantially symmetrical with respect to the vertical center line. By reason of this symmetrical shape it follows that when the rail goes through pass No. 3 the two flanges R R' are formed of substantially equal lengths.

After the passage through pass No. 3 the subsequent steps are concerned chiefly in bending and reducing the several parts to the exact shape and dimensions of the final product desired. Fig. 5 illustrates pass No. 4 in which the rail is passed in an upright position between flat rolls which bend down the flanges R R' to a substantially horizontal position from the upwardly inclined position indicated in dotted lines. In Fig. 6 the bar is shown laid on its side in pass No. 5, the principal effect of which is to reduce the width of the base flange X and the thickness of the web, and also to some extent the thickness of the head flanges R R' . In order to obtain the final reduction of the thickness of the flanges R R' which is necessary if they are to conform to the base X of the finished beam the bar is rolled through pass No. 6 (Fig. 7). Here the horizontal rolls T and U hold the web of the bar and reduce the same in thickness, preferably also reducing to some extent and to its final width the base X . The roll W acting with a pressure in line with the web effects a considerable reduction in the thickness of the flanges R R' and brings them finally to the desired dimensions.

The processes described may be considerably modified within the invention by submitting the rail to two or more operations to accomplish the changes which I have indicated as being accomplished in a single pass; or by omitting one or more of the operations which I have shown as desirable to secure a final product of peculiar shape or dimensions.

These are matters which are quite within the skill of persons familiar with this art. Also the contours of the rolls or of the passes between the rolls may be modified within certain limits. The I-beams for example instead of having the flanges reduced to ex-

actly the same cross-sectional area may be left with one flange heavier than the other, since this is not a disadvantageous construction and is of course cheaper than continuing the rolling to bring the larger flange down to the same section as the smaller. Also the several steps or subprocesses are capable of use in many cases independently of the other steps constituting the complete process described. For example in Fig. 8 is indicated a method of producing an I-beam from the girder rail having a head of peculiar shape with two flanges already formed. The conversion of such a rail into an I-beam, (or into a γ) does not call for the grooving and flanging of the head but merely for the reshaping and reducing of the flanges R and R' already provided. Where these flanges are very much wider than the flanges of the finished product their edges may be sheared off to the desired width. Therefore though I have described with great particularity of detail embodiments of the invention, yet it is to be understood that the invention is not limited to the specific structure or processes disclosed. Various modifications thereof may be made by those skilled in the art without departure from the invention.

What I claim is:

1. In converting a worn rail into an I-beam, the process which consists in subjecting it to the following rolling and bending operations, namely: rolling the top of the rail head flat to make it substantially symmetrical with respect to the center line of the web, rolling down the under faces of the head to form a taper S more nearly parallel with the web, rolling down a groove in the top of the head to form two upwardly inclined flanges, the taper S being such as to insure that the thickness of said flanges at the points where they meet the web shall be at least as great as their thickness at their outer edges, holding the web between opposite rolls and supporting the under faces of the head in a direction upwardly inclined from the web and approximately parallel to the upper faces of the flanges being formed by said grooving operation, bending down said flanges to a position substantially perpendicular to the web, and rolling down the rail base to reduce its width and the said flanges to reduce their thickness until the said rail base and the opposite head formed by said flanges are substantially equal in width and thickness respectively, and simultaneously rolling down the web to reduce its thickness correspondingly.

2. In converting a rail into an I-beam or the like, the process which consists in reshaping the under faces of the head by rolling it down to form a taper S more nearly parallel with the web, rolling down a groove in

the top of the head to form two upwardly inclined flanges, the taper **S** being such as to insure that the thickness of said flanges at the points where they meet the web shall be 5 at least as great as the thickness at their outer faces, supporting the under faces of the head in a direction upwardly inclined from the web and approximately parallel to the upper faces of the flanges being formed 10 by said grooving operation, and bending

down said flanges to a substantially horizontal position.

In witness whereof, I have hereunto signed my name in the presence of two subscribing witnesses.

JAMES E. YORK.
